UNITED STATES PATENT OFFICE.

WILLIAM C. HANSON, OF PITTSBURG, PENNSYLVANIA.

COIN-RECEIVER FOR VENDING-MACHINES.

No. 896,012.

Specification of Letters Patent.

Patented Aug. 11, 1908.

Application filed March 28, 1908. Serial No. 423,877.

To all whom it may concern:

Be it known that I, WILLIAM C. HANSON, a resident of Pittsburgh, in the county of Allegheny and State of Pennsylvania, have invented certain new and useful Improvements in Coin-receivers for Vending-Machines, of which the following is a specification.

The primary object of this invention is to provide for the projecting of coins into vending machines and other coin apparatus in such manner that the coin is absolutely beyond the control of the operator after it has passed from the coin receiver, and cannot be withdrawn.

A coin receiver has been proposed wherein a portion of the coin is exposed through the end of a coin passage, the bottom of the passage being inclined so that the coin will roll to and remain in this exposed position. The operator then strikes the coin and projects it through the passage and into the apparatus. This form of receiver is open to the objection that a string or wire may be fastened to the coin and follow it through the open end of the receiver and into the machine, thus rendering it easy to withdraw the coin after it has performed its function.

The present embodiment is designed to obviate such fraudulent practice without materially changing the method of operation, the coin being held by gravity in starting position and projected by the operator into the machine with greater or less force as desired. But instead of exposing the coin to receive the projecting blow, a projecting device or knocker is movably mounted in the coin passage, in the preferred adaptation having limited swinging movement therein, and so arranged as to completely fill the heretofore open end of the passage and render it quite impossible for a wire or other retracting device to follow the coin into the machine.

An adaptation of the invention is shown in the accompanying drawings, Figure 1 being a side elevation of the receiver, and Fig. 2 a similar view with the face plate removed. Fig. 3 is an edge view. Fig. 4 is a top plan, and Fig. 5 a bottom plan. Fig. 6 is a cross-section on line 6—6 of Fig. 1.

Referring to the drawings, 2 designates the body of the casing which is flanged top and bottom to provide a coin passage or space within the casing of the width required for a penny, five cent piece, or other coin. The casing is closed by the face plate 3 riveted to the flanges as shown. It will be understood

that the inner end 4 of the casing may be extended as desired and secured in any suitable manner to the vending machine or other coin apparatus on which the receiver is used. 60

In the top edge of the receiver is the coin-inserting slot 5, and on opposite sides are the slots or openings 6 through which the coin C may be seen after it is dropped through slot 5. Bottom 7 of the coin passage slopes 65 downwardly toward the outer end of the receiver and directs and holds the coin into edgewise engagement with the coin projector.

In the present embodiment, the projector 70 consists of a flat piece of metal 8 pivoted at its upper end to the casing as indicated at 9, the projector being positioned within and closing the outer end of the coin passage formed within casing 2. The projector is so 75 mounted that its outwardly rounded outer portion normally projects from the casing, with extension 8' at the lower end of the projector within slot 7' and bearing against the outer end 10 of the slot, while the inward 80 movement of the projector is arrested by said extension striking the inner end 10' of the slot. Thus said ends comprise stops between which the projector operates and define the extent of movement thereof. Slot 7' 85 is also of service in preventing dirt from accumulating in the otherwise closed bottom of the passage.

The operation will be obvious. After the coin has been inserted and rolls to the full 90 line position shown in Fig. 2 with its edge bearing against the pivoted projector, the extended portion of the latter is struck by the operator and the coin thereby projected forwardly through the passage and into the 95 machine. The coin may be passed forward at more or less speed determined by the force of a blow on projector 8 and thus thrown a longer or shorter distance into the machine, at the pleasure of the operator. 100 The projector so closes the end of the coin passage that it is absolutely impossible to attach a wire or other retracting device to the coin. Fraudulent practice of this kind is impossible through the inserting slot 5, as 105 with a cord or wire passed thereinto the coin cannot be readily manipulated and withdrawn after it has been once projected into the machine.

I claim:

1. The combination of a casing having a coin passage with a coin-inserting slot com-

municating with the passage, a coin projecting device having swinging movement within the coin passage and normally projecting from the passage, and means for limiting such movement.

2. The combination of a casing having a coin passage with a coin-inserting slot communicating with the passage, the passage opening through the outer end of the casing, 10 a coin projector pivoted to oscillate within the open outer end with a portion of the projector normally exposed at said end, and means for limiting such oscillating movement.

15. 3. The combination of a casing having a coin passage with a coin-inserting slot communicating with the passage, said passage opening through the outer end of the casing, a coin projector within the outer end of the 20 passage and at its upper end pivoted to the casing, stop means for limiting the inward and outward movement of the projector, a portion of the projector being normally exposed through the open end of the passage.

25. 4. The combination of a casing having a coin passage with a coin-inserting slot communicating with the passage, the passage

opening through the outer end of the casing and the bottom of the passage sloping toward said end, a coin projector in the end of 30 the passage and normally partially extending therefrom, the projector being pivoted at its upper end to the casing, an extension on the lower end of the projector, and two stops at the bottom of the passage between 35 which the extension moves and defining the extent of movement of the projector.

5. The combination of a casing having a coin passage with a coin inserting slot communicating with the passage, the passage 40 shaped to hold an inserted coin normally in the outer portion thereof, and a coin propelling device movable in the outer portion of the passage for projecting the coin inwardly through said passage, the propelling 45 device being normally exposed to be struck by the operator.

In testimony whereof I affix my signature in presence of two witnesses.

WM. C. HANSON.
